UNITED STATES PATENT OFFICE

ALEJANDRO CALBO ALEMANY, OF AGRES, SPAIN

WRENCH

Application filed January 3, 1931, Serial No. 506,461, and in Spain August 27, 1930.

This invention relates to wrenches and has for its object the provision of mechanical wrenches for use with all kinds of nuts and which can be operated almost instantaneously.

According to the invention the wrench comprises in combination a fixed jaw with a handle rigidly attached thereto, a hand-operated screw-threaded member located in the said handle and a movable jaw slidable relatively to the said fixed jaw and formed with an inclined surface which is engaged by the said screw-threaded member for the purpose of causing the movable jaw to slide relatively to the fixed jaw. The operation of sliding the movable jaw towards the fixed jaw may be effected positively by co-operation with the inclined surface of the screw-threaded member. The movable jaw may be pressed apart from the fixed jaw under the action of a spring which may engage an over-hanging lip formed on the movable jaw.

The screw-threaded member may be formed at one end with a screw-threaded portion co-operating with a screw-threaded section in the handle close to the jaws, and at its other end with a spiral groove which is engaged by a nut member capable of sliding in the handle. The nut member may slide in grooves or channels formed in the handle, and be formed with a projection engaging the spiral groove in the screw-threaded member.

The movable jaw or a part thereof may be located in a space or groove formed in the fixed jaw.

The invention will be further described with reference to the accompanying drawing in which:—

Figure 1 shows a side view, partly in section, of the wrench,

Figure 2 a side view of the movable jaw,

Figure 3 a cross sectional view of the movable jaw, and

Figure 4 a side view of the fixed jaw.

Referring to the drawing, the letter *a* indicates the fixed jaw which is formed in a piece with the wrench handle *l* and *b* the movable jaw of the wrench; *c* is a guide groove in the movable jaw; the movable jaw *b* is

formed with an over-hanging lip *d* upon which the free end of a spring *e* presses; the other end of the said spring *e* being attached to the handle *l* of the wrench at *g*, and tending to keep the movable jaw *b* open and separated from the fixed jaw *a*; *f* is a threaded portion through which runs the top part of a spiral screw *h*, *h'*. The said spiral screw *h*, *h'* of the sliding jaw is formed with two different screw threads; the shorter thread *h* in the top part is a screw thread co-operating with the screw threaded portion *f* and the longer thread *h'* in the lower part of the handle is spiral; *i* is a cavity in the handle of the wrench in which is located the spiral screw *h'*; *j* are two guides in the sides of the cavity in the handle *l* on which rests and slides a running nut *K* formed with a projection *h* engaging the spiral screw *h'*. The said nut *K* when reciprocated raises and lowers, according to whether it is propelled upwards or downwards, the spiral screw *h'* which on rising makes the inclined plane of the movable jaw *b* glide along its upper end drawing the movable jaw *b* towards the fixed jaw *a*. On descending, the spring *e* acts upon the lip *d* of the movable jaw *b* and causes it to slide relatively and to be separated from the fixed jaw *a*.

I claim:

1. A wrench comprising a fixed jaw, a hollow handle rigidly attached to said fixed jaw, a movable jaw slidable relative to said fixed jaw and having inclined surface, a hand operable oppositely screw-threaded member located in said handle engaging said inclined surface of said movable jaw and means cooperating with the opposite screw threads upon said member for reciprocating said screw member.

2. A wrench comprising a fixed jaw, a hollow handle, rigidly attached to said fixed jaw, a movable jaw slidable relatively to said fixed jaw, an over hanging lip formed on said movable jaw, a spring attached to said handle engaging said over hanging lip, and a hand operable oppositely screw threaded member located in said handle cooperating with said movable jaw and means cooperating with said opposite threads upon said mem-

ber for reciprocating said member and thereby operating the movable jaw in one direction while the spring operates the movable jaw in the other.

5 3. A wrench comprising in combination a fixed jaw, a hollow handle rigidly attached to said fixed jaw, a movable jaw slideable relatively to said fixed jaw having inclined surface, a hand operable oppositely screw-

10 threaded member located in said handle engaging said inclined surface of said movable jaw, means cooperating with said opposite screw-threads for reciprocating said member, an over hanging lip formed on said movable

15 jaw and a spring attached to said handle engaging said over hanging lip.

4. A wrench comprising in combination a fixed jaw, a hollow handle attached to said fixed jaw having a screw-threaded portion

20 adjacent said fixed jaw, a movable jaw slideable relatively to said fixed jaw having an inclined surface, an overhanging lip formed on said movable jaw, a spring attached to said handle engaging said overhanging lip, a

25 hand operable member located in said handle and engaging said inclined surface of said movable jaw, said hand operable member having oppositely screw threaded portion one of said portions cooperating with said screw-

30 threaded portion upon said handle.

5. A wrench comprising a fixed jaw, a hollow handle rigidly attached to said fixed jaw having longitudinal grooves therein, a movable jaw slideable relatively to said fixed jaw

35 having an inclined surface, an overhanging lip formed on said movable jaw, a spring attached to said handle engaging said overhanging lip, a hand operable member located in said handle engaging said inclined sur-

40 face of said movable jaw having a spiral groove therein, and a nut member sliding in said longitudinal grooves having a projection cooperating with said spiral groove in said member.

45 6. A wrench comprising a fixed jaw, a hollow handle rigidly attached to said fixed jaw having a screw-threaded portion adjacent said fixed jaw, said handle having longitudinal grooves therein, a movable jaw slideable

50 relative to said fixed jaw, having an inclined surface, an overhanging lip formed on said movable jaw, a spring attached to said handle engaging said overhanging lip, a hand oper-

55 able member located in said handle engaging said inclined surface of said movable jaw, said hand operable member having a screw-threaded portion cooperating with said screw-threaded portion upon said handle, said hand

60 operable member also having an oppositely disposed spiral groove and a nut member sliding in said longitudinal grooves having a portion cooperating with said spiral groove.

In testimony whereof I have signed my name to this specification.

65 ALEJANDRO CALBO ALEMANY.
